UNITED STATES PATENT OFFICE

2,690,013

INSTRUMENT FOR DRAWING ELLIPSES

William E. MacGuire, Louisville, Ky.; Carolyn E. MacGuire, administratrix of said William E. MacGuire, deceased

Application June 6, 1952, Serial No. 292,161

2 Claims. (Cl. 33—30)

1

This invention relates generally to the class of geometrical instruments and is directed particularly to an improved instrument for drawing or laying out ellipses.

A principal object of the present invention is to provide an instrument in the nature of a compass by means of which an ellipse may be drawn easily and quickly in one complete rotative movement of a marking implement around a fixed center.

Another object of the invention is to provide an instrument of the character stated wherein means is provided for making an easy and quick adjustment of the instrument for the laying out of ellipses having major and minor axes of different lengths as required.

Still another object of the invention is to provide an instrument of the character stated employing a fixed standard and a marking implement carrying arm which is pivoted to the standard for turning movement thereabout and for swinging movement inwardly and outwardly relative thereto, wherein the dimensions of the desired ellipse are controlled by a single cam element carried by the standard which functions as a guide to move the arm inwardly and outwardly relative to the standard as the arm is turned around the standard.

Still another object of the invention is to provide, in an implement of the above described character, a novel means whereby the marking implement is maintained at all times in contact with the marking surface as the arm swings inwardly and outwardly relative to the standard during its turning movement around the standard.

A still further object of the invention is to provide in an instrument of the character above set forth, a means whereby the major and minor axes of the ellipse desired to be laid off, can be altered by movement of the cam member longitudinally of the standard and by oscillation of the cam member on an axis extending transversely of the standard.

Other objects and advantages of the invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

2

In the drawings:

Figure 1 is a view in elevation of an instrument constructed in accordance with the preferred embodiment of the present invention.

5 Figure 2 is a longitudinal section taken substantially on the line 2—2 of Figure 1.

Figure 3 is an exploded view of the fixed standard and parts carried thereby exclusive of the marker carrying arm.

10 Figure 4 is a sectional view of the cam disk turning annulus carried by the arm.

Figure 5 is a detail view illustrating the connection between the lower end of the arm and the clevis of the marking element.

15 Figure 6 is a view in elevation of a ruling pen to be used in the marking element.

Figure 7 is a view in side elevation of the instrument showing the attachment of the extension bar and the additional supporting leg.

20 Figure 8 is a view in plan of the bifurcated leg.

Figure 9 is a transverse section taken on the line 9—9 of Figure 7.

Referring more specifically to the drawings it 25 will be seen upon reference to Figure 1 that the instrument of the present invention is generally in the nature of a compass in that it comprises a standard 10 which has one end placed upon the surface on which the ellipse is drawn, and an arm 12 which is pivotally coupled at one end to the standard and carries a marking implement upon its other end as hereinafter more specifically described.

The standard 10 carries upon its lower or bottom end an element for maintaining the standard in fixed position on the marking surface, such element being here shown as in the nature of a circular foot member 14 having an upstanding collar 16 in which the lower end of the standard 30 10 is fixed. The base of the foot member 14 carries a number of downwardly directed, equidistantly spaced surface engaging pins 18 which hold the foot against slipping.

The upper end of the standard 10 has a portion 10a of reduced diameter whereby there is provided a surrounding shoulder 20. The reduced portion 10a extends entirely to the upper end of the standard and is provided with a transverse aperture 22 for the purpose about to be described.

40 45 The upper end of the standard carries a rotary head which is generally designated 24.

The head 24 comprises a lower plate 26 which is formed integral with the elongate hub 28 through which and the plate, is formed a passage 50 55 30 of a diameter to snugly receive the reduced

portion 10a of the standard. The hub, as shown, rests upon the shoulder 20 and is thereby maintained against downward movement on the standard.

Lying upon the top of the plate 26 is a spring plate 31 which has a central aperture 32 for the portion 10a of the standard and resting upon the spring plate is a control or turning disk 33 which also has a central aperture 34 to receive the portion 10a of the standard.

The three disks or blades 26, 31 and 33 lie in superimposed relation and are coupled together by screws 35 which pass through aligned apertures 36, 37 and 38 of the members, the screws being threaded into the apertures 38 in the disk thereby binding the three members together.

Formed integral with the spring plate 31 is a curved leaf spring 39 which extends outwardly, downwardly and inwardly from the edge of the plate 31 and terminates in the finger 40 which is of a reduced width. The purpose of this spring is hereinafter set forth.

The top of the disk 33 is laid off in degrees of the circle, for the purpose hereinafter pointed out, and resting upon the top of the disk 33 is a cover disk 41 which is of slightly smaller diameter than the disk 33 and has a recess 42 in the edge thereof, through which one of the degree indicating members on the top surface of the underlying disk 33 may be read. The cover disk 41 is also centrally apertured with a guide collar 43 defining the aperture and the upper end of the standard passes through this collar and has fixed thereto, just above the collar, by the transverse pin 44, the knurled cap 45.

As the cap 45 is fixed to the upper end of the standard and the head 24 rests on the shoulder 20 just below the cap it will be seen that the head is free to turn or rotate about the standard but is prevented from having any material movement lengthwise thereof.

The numeral 46 generally designates the axis determining unit. This unit comprises a relatively long sleeve 47 through which the standard, below the shoulder 20 passes and which is designed to have movements up and down on the standard.

The sleeve 47 has a head 47a upon its upper end and at its lower end it carries the lock screw 48 which has the reduced finger 48a on its inner end which engages in a keyway or key slot 49 formed in the standard 10 from the foot to the shoulder thereof.

The sleeve head 47a has the oppositely positioned radially directed pivot pin holes 50 therein which extend to the interior of the sleeve for the purpose hereinafter set forth and between the sleeve head 47a and the lock screw 48, the sleeve is externally screw threaded as indicated at 51.

Threaded on the sleeve 47 is the cam disk positioning nut 52 which is defined at its top by the outstanding encircling shoulder 53.

Also threaded upon the sleeve 47 below the disk positioning nut 52, is a lock nut 54 which holds the nut 52 in set position.

The numeral 55 designates the axis control cam which is in the form of a disk as shown, having an elongate, relatively wide slot 56 formed diametrically therein. This slot is of a width to receive the sleeve head 47 and extending into the slot from opposite sides, centrally of the ends of the slot, are the pivot pins 58 which enter the holes 50 and engage, at their inner ends, against the standard 10. These

pivot pins, which are positioned diametrically of the disk 55 at right angles to the slot 56, are urged inwardly by springs 59 which are held by the screws 60.

It will be seen from the foregoing that the axis control cam may be rocked on its pivots 58 and the extent of such rocking movement is governed by the position of the positioning nut 52, the rim 53 of which is engaged by the disk 55 when the latter is oscillated to a predetermined extent.

The arm 12 has the curved shoulder 61 at its upper end which joins the two spaced ears 62. These ears receive between them the hub 28 and they have extended through them and into the hub, the screw pivot pins 63 which are aligned transversely of the standard 10 so that the arm 12 may swing on an axis perpendicular to the standard and passing through the longitudinal center of the latter.

The outer side of the shoulder, which is the side facing away from the ears 62, has the wall 64 between the ears 62 on which bears the reduced end 40 of the leaf spring 39. This spring 39 is tensioned to move its free end inwardly toward the standard and accordingly it constantly exerts inwardly pressure against the upper end of the arm tending to swing the arm toward the standard.

The lower end of the arm 12 is reduced or flattened to provide the hinge blade 65 for the purpose hereinafter set forth and between the blade 65 and shoulder 61 the outer side of the arm 12 is provided with the flat surface 66.

The numeral 67 generally designates the cam disk trip which comprises a collar 68 which encircles the arm 12 and which has the opening 69 thereof flattened on one side as indicated at 69a, such flattened side engaging the flat surface 66 of the arm thereby holding the collar against turning on the arm.

The collar 68 carries a locking screw 70 which extends through the flat surface 69a for contact with the flat surface 66 of the arm whereby the collar is fixed in adjusted position on the arm.

The underside of the collar 68 carries on the side of the arm receiving opening 69 opposite from the locking screw 70, a downwardly directed spring pressed pin 71, the control spring for which is designated 72 and the spring and pin are encased in a suitable sleeve 73 carried on the underside of the collar. This pin 71 is designed for contact with the top surface of the axis control disk 55 as will be hereinafter set forth.

The numeral 74 generally designates the marking implement or marking unit which is carried on the free end of the arm 12. This unit comprises an elongate sleeve or cylinder 75 through the upper end of which is threaded a spring compressing screw 76 which engages at its end, the top end of a coil spring 77 which is housed in the cylinder 74 as shown.

Extending into the cylinder through the open lower end thereof is the shank 78 of a marker or scribe 79 which may be in the form of a pencil as indicated in Figure 1 and 2 or in the form of a ruling pen as illustrated in Figure 6 and designated 79a.

The shank 78 of the marking or scribing element has the longitudinal key slot 80 formed therein, in which is engaged the inner end of the retaining screw 81 which is threaded through the side wall of the cylinder 74 at the lower end thereof. Since the key slot 80 does not extend

all of the way to the upper end of the shank 78 it will be seen that the spring 77 can move the shank of the marking element outwardly without danger of having the element escape from the cylinder.

Formed integral with the lower end of the cylinder 74 is a coupling clevis comprising two spaced ear members 82 between which the tongue 65 of the arm 12 is adapted to position to receive the threaded pivot pin 83. The ears 82 of the clevis are directed obliquely upwardly from the lower end of the cylinder 74 so that when the marking implement is coupled with the lower end of the arm 12 such implement will have the scribe disposed substantially vertically for contact with the marking surface.

It is believed to be apparent from the foregoing that the spring 39 will normally hold the marker arm 12 against the edge or periphery of the cam disk 55 so that as the head 24 is rotated the arm 12 will move around the disk and if the disk 55 is set in a plane which is at an angle to the standard 10 other than a right angle the arm 12 will swing outwardly and inwardly during this rotary movement.

As the arm swings outwardly at its lower end from the standard 10 such lower end will, of course, rise from the surface but due to the action of the spring 77, as the arm and cylinder rise the marking element will be moved outwardly or downwardly so that the marking point will be kept in contact with the marking surface.

In the use of the instrument, the standard 10 is, of course, set upon the marking surface to be at the point of intersection of the long and short axes of the ellipse which is to be laid out.

The length of the long axis of the ellipse is determined by the height of the disk 55 on the standard 10 as it will be seen that the long axis of the ellipse will be parallel to the turning axis of the disk 55.

After the proper elevation of the disk on the standard is determined, the disk positioning nut 52 is elevated to swing the disk 55 to a horizontal position or a position in a plane perpendicular to the standard 10. The collar 68 is located, before this adjustment, above the disk 55 and after the disk has been turned to the horizontal position the collar 67 is lowered until the plunger 71 contacts the top surface of the disk whereupon the collar is fixed.

The disk positioning nut is then lowered from the disk and the disk swung into an oblique plane with respect to the standard until it is in proper position where, with the arm 12 against the low edge of the disk, the marker 79 will designate a point on the marking surface a distance from the standard equal to half the length of the short axis of the ellipse. The lock nut 54 is then set to prevent the disk from swinging beyond its selected inclined position.

The ellipse may now be drawn by grasping the disk 33 and rotating the head 24 so as to swing the marker unit around the standard. If the starting position of the arm 12 is with the arm in contact with the lowermost part of the periphery of the disk 55, the arm as it rides along the rising edge of the disk will swing outwardly from the standard so as to mark off a line leading to one end of the long axis of the ellipse and when the arm reaches a position where the trip plunger or pin 71 rides across the axis of the pivot pins 58, the trip pin will effect the oscillation of the disk 55 to a reverse angle whereupon the arm will continue riding along the edge of the disk down

the sloping side toward the end of the short axis of the ellipse. The stated action up to this point will then be duplicated as the arm moves around to its starting position to complete the outlining of the ellipse, by the marking unit, on the marking surface.

As previously stated, as the arm swings outwardly away from the standard and naturally tends to rise at its outer end together with the cylinder 74, the marking element will be maintained in contact with the marking surface by the action of the spring 77 sliding the marking element downwardly and outwardly from the cylinder, and of course, as the short axis side of the ellipse is approached the arm 12 will swing inwardly and upward pressure will be applied to the marking element so as to compress the spring 77.

Where it may be necessary to reach out from the standard 10 to a greater distance than would be convenient to the use of the marking unit applied directly to the lower end of the arm 12, use may be made of the extension arm 12a as illustrated in Figure 7. This extension arm 12a comprises a bar of suitable length, designated 12b, having at one end the angularly extending tongue 12c and at the opposite end the oppositely directed angularly extending clevis comprising the two spaced parallel tongues 12d. The tongue and clevis are disposed to form an obtuse angle with the bar and are in oppositely directed but parallel relation as shown. Thus when the terminal blade 65 of the arm 12 is located between the apertured ears 12d and secured thereto by the screw 83, the tongue 12c can be disposed at the proper downwardly extending angle for proper connection with the side extension 82 of the cylinder 74 of the marking implement.

In order to give further stability to the instrument, particularly when use may be made of the extension arm 12a, an auxiliary brace leg is provided such as that shown in Figure 7 and generally designated 85. This auxiliary leg comprises the fork 86 having at its top a stem 87, and an angled sleeve 88, in one end of which the stem 87 is positioned and secured by a screw 89 while at the other end of the sleeve is a spring clasp or clip 90 which extends laterally from the sleeve at right angles thereto and which is adapted to frictionally engage around the standard 10 as illustrated.

From the foregoing it will be readily apparent that there is provided by the present invention an instrument of novel construction by means of which accurate ellipses may be formed easily and quickly by one continuous turning movement of the marking implement around the central positioning standard. It will also be apparent that by the novel employment of the obliquely disposed disk and manner in which it is mounted so that it can be raised or lowered as desired according to the length of the long axis required or disposed at a desired angle in accordance with the length of the short axis desired, changes can be made easily and quickly for the easy and accurate formation of ellipses of different dimensions.

I claim:

1. An instrument for drawing ellipses, comprising a vertical standard, a foot on the lower end of said standard to support the same on a surface on which an ellipse is to be drawn, a head unit mounted for turning movements on the top end of said standard, an arm pivotally coupled at one end to the head unit to swing relative to the standard on an axis perpendicular to the standard, said

arm being turnable with said head unit about the standard, a vertically disposed marking implement, a link having reversely curved end portions pivotally connected to and extending between said arm and said implement, a circular disk having a central opening engaged on said standard, adjustable pivot means supporting said disk on said standard, the perimeter of said disk being traversed by the arm as it is turned with the head unit relatively to the standard for guiding the implement in the desired path, and spring means cooperative with said implement for maintaining the same in contact with said surface, the upper end of said standard being reduced in diameter to provide an annular shoulder upon which the head unit is seated, said head unit being comprised in a lower disk having a hub engaged over said shoulder, the upper end of said arm having an angled portion which is bifurcated to straddle said hub, pivot pins threaded into said hub through apertures formed in the side portions of the bifurcation, a second disk supported on the first disk, an arcuate leaf spring depending from the periphery of said second disk and having an end bearing against the outer side of said arm, a third disk supported on said second disk and having its top face calibrated in degrees, fastening elements securing said disks together, a cover disk supported on said third disk and having a aperture through which the degree calibrations on the latter may be viewed, and a cap element secured on the top end of said standard to prevent endwise movement of the disk assembly on the standard.

2. An instrument for drawing ellipses, comprising a vertical standard, a foot on the lower end of said standard to support the same on a surface on which an ellipse is to be drawn, a head unit mounted for turning movements on the top end of said standard, an arm pivotally coupled at one end to the head unit to swing relative to the standard on an axis perpendicular to the stand-

ard, said arm being turnable with said head unit about the standard, a vertically disposed marking implement, a link having reversely curved end portion pivotally connected to and extending between said arm and said implement, a circular disk having a central opening engaged on said standard, adjustable pivot means supporting said disk on said standard, the perimeter of said disk being traversed by the arm as it is turned with the head unit relatively to the standard for guiding the implement in the desired path, and spring means cooperative with said implement for maintaining the same in contact with said surface, the said adjustable pivot means comprising an exteriorly threaded sleeve slidable on an intermediate portion of said standard, a set screw carried by said sleeve for its securement in desired position on said standard, the said guide disk being pivotally mounted in the upper end of said sleeve, a nut threaded on said sleeve, an annular shoulder at the upper end of said nut to support said guide disk in required angular relation with respect to said standard and said arm.
